UNITED STATES PATENT OFFICE.

HAROLD E. McCRAY, OF WATERLOO, IOWA, ASSIGNOR TO JOHN DEERE TRACTOR COMPANY, OF WATERLOO, IOWA, A CORPORATION OF IOWA.

INTERNAL-COMBUSTION ENGINE.

Application filed February 15, 1923. Serial No. 619,081.

My invention relates to internal combustion engines of the horizontal type such as are commonly used for operating farm machinery, and has for its object to improve the 5 construction of such engines in various respects which will be hereinafter specifically pointed out in connection with the description of the embodiment thereof illustrated in the accompanying drawings. What I re- 10 gard as new is set forth in the claims.

In the accompanying drawings,—

Fig. 1 is a side elevation of my improved engine, some parts being in section;

Fig. 2 is a plan view thereof;

Fig. 3 is a partial central longitudinal vertical section of the engine on line 3—3 of Fig. 2 showing the inner portion of the cylinder, the piston, the crank case and fuel tank, and some of the operating parts contained within the crank case;

Fig. 4 is a partial side elevation, the cover plate at that side of the engine being removed to expose the governing devices by which the operation of the exhaust valve 25 and the ignition devices is controlled;

Fig. 5 is a vertical cross-section on line 5—5 of Fig. 4;

Fig. 6 is a partial end view of the left-hand end of the engine as shown in Fig. 1;

Fig. 7 is a perspective view of the rocking 30 detent which forms a part of the governing mechanism for controlling the operation of the exhaust valve and the ignition devices;

Fig. 8 is a horizontal cross-section on line 33 8—8 of Fig. 6;

Fig. 9 is a front elevation of the muffler;

Fig. 10 is a partial vertical cross-section on line 10—10 of Fig. 4;

Fig. 11 is a partial cross-sectional view 40 showing the magneto mounting and the driving connections thereof;

Fig. 12 is a perspective view of one of the upper crank shaft bearing blocks; and

Fig. 13 is a section on line 13—13 of Fig. 8.

My improved engine comprises a hollow base 13 in the form of a casting adapted to be bolted, or otherwise suitably secured to a supporting plate 14 of wood or other suitable material, and to contain within it a fuel tank 15, which, as best shown in Fig. 3, occupies the greater portion of the base 13. The fuel tank is in the form of a pan or box of suitable dimensions to fit into the base 13, and provided at its upper margins with an

outwardly-extending flange 16 which overlies an inwardly-projecting flange 17 at the upper margin of the base, the arrangement being such that the fuel tank is supported so that its bottom is slightly above the plate 14. A cover plate 18 fits over the fuel tank 55 15, its marginal portions resting on the flanges 16 as shown in Fig. 3, and upon the margins of this cover plate rest the marginal portions of a crank case 19 which is securely bolted to the base 13 by bolts 20, as best 60 shown in Fig. 1. By this construction the cover plate 18 serves not only as the top of the fuel tank but also as the bottom of the crank case. For the purpose of filling the fuel tank, the crank case 19 is provided at 65 some convenient point, preferably at its outer end, with a passage 21 which leads to a filling opening 22 in the cover plate 18, as best shown in Fig. 3. The passage 21 is adapted to be closed by a plug 23 or other suitable 70 means. As shown the said passage is formed in a boss 24 projecting from the lower portion of the crank case, and the inner wall of said crank case is extended diagonally downward, as shown at 25 in Fig. 3, so as to bear 75 upon the cover plate 18 around the inner margin of the opening 22 so that a tight fit around said opening is obtained. Preferably a gasket 26 is placed between the lower marginal surface of the crank case and 80 cover plate 18 to prevent leakage of oil from the crank case. Fuel is delivered from the fuel tank through a pipe 27, connected with the inner end of said tank at the bottom thereof, and having at its outer end a plug 85 28 by the removal of which the tank may be emptied when desired. Leading from the pipe 27 is a check-valve 29, preferably of the ball type, with which connects a supply pipe 30 leading to the fuel inlet of the engine cylinder. As shown in Fig. 3, the pipe 27 and check-valve 29 are both located within the base 13, the check-valve 29 being preferably in the form of an elbow casting one 90 end of which extends through an opening 31 in the base so that the supply pipe 30 may be conveniently connected therewith by a coupling 32. By this construction the check-valve 29 is protected and is not apt to be damaged in transporting the engine, as when 95 the pipe 30 is uncoupled none of the parts connected with the fuel tank project beyond the base. Also, the arrangement of the fuel

tank within the base is advantageous not only because said tank is well protected, but also because space is economized.

The crank case 19 constitutes also the main engine frame, since cast integral with it is a cylinder block 33 and water hopper or tank 34, as best shown in Figs. 1 and 3. Referring particularly to Fig. 3,—35 indicates the engine cylinder which extends through the lower portion of the water hopper 34, but is separated therefrom laterally so that the water in the hopper 34 surrounds said cylinder. In the bottom of the cylinder block is an opening having a plug 36, through 15 which the water in the hopper may be drawn off.

The crank case portion of the engine frame is provided with a removable cover 37 which is held in place preferably by bolts 38 at opposite sides thereof near the crank case end of the engine, and by an intermediate bolt 39 which extends diagonally through a boss 40 in the cover plate 37 into a boss 41 in the portion of the engine frame which 25 forms the inner wall of the water hopper 34, as shown in Figs. 2 and 3. A suitable gasket placed between the cover 37 and the engine frame makes the cover oil tight. By removing the cover plate 37 access may be had conveniently to the operating parts in the crank case, all of which are thereby fully exposed.

Extending transversely of the crank case is a crank shaft 42, the crank portion of which is indicated by 43. The end portions of said crank shaft are mounted in suitable bearings in the side walls of the crank case 19, the lower bearing being shown at 44 and the upper bearing at 45 in Figs. 1 and 4. As therein shown the side walls of the crank case adjacent to these bearings are cut away so that the lower bearings are formed in depressed portions or recesses in said side walls. The upper bearings 45 are formed in removable blocks 46 which fit into these recesses and are held in place by bolts 47, so that they also serve as part of the oil tight closure for the crank case. The construction of the blocks 46 is best shown in Fig. 12, from an inspection of which it will be seen that said blocks are adapted to be slid vertically into the recesses referred to, and consequently the walls of the crank case hold said blocks against endwise movement so that there is no lateral strain on the bolts 47. Adjacent to these recesses the side walls of the crank case are strengthened and widened by lateral flanges or extensions 48, as best shown in Fig. 2, so that wide bearing surfaces are provided for the ends of the blocks 46 and they are strongly supported. The bearings 44, 45 are provided with the usual anti-friction linings 49, as shown in Figs. 1 and 4. By removing the cover 37 and blocks 46 the

crank shaft may readily be removed as occasion may require.

Referring now to Fig. 3, 50 indicates the piston which operates in the cylinder 35, said piston being connected by a pitman 51 with the crank portion 43 of the crank shaft, which, as best shown in Fig. 2, is preferably provided with two fly-wheels 52, 53, one at each side of the engine. 54 indicates a magneto which is mounted on the crank case at one side thereof between the crank shaft and the water hopper, as best shown in Figs. 1 and 2, and below the position of the magneto is a chamber 55, as best shown in Fig. 5, having a laterally-disposed cover plate 56, so which contains certain controlling mechanism which will be hereinafter described. The cover plate 56 is removable so that access may be had to said chamber, and it is held in place by screws 57, as shown in Figs. 1 and 5.

The magneto 54 is driven from the crank shaft 42 by means of a train of gears inside the crank case and subject to lubrication by the splash system, comprising a pinion 58 mounted on the armature shaft 59 of the magneto and having a collar 58^a which projects through a slot in the crank case cover, as shown in Fig. 11, a gear 60 mounted on a transverse shaft 61 journaled in one of the side walls 19^a of the crank case, as shown in Fig. 5, and a pinion 62 mounted on the crank shaft 42, as shown in Fig. 3. The collar 58^a serves to keep oil out of the magneto, and the slot in the cover 37 permits the cover to be removed without disturbing the magneto setting. To make a tight closure at this point the cover is provided with a separate removable plate 37^a and gasket 37^b, as shown in Fig. 11.

As indicated in Fig. 3, the lower portion of the crank case serves as an oil reservoir, oil being supplied thereto through a pipe 63, best shown in Fig. 1 and indicated by dotted lines in Fig. 3. This pipe is preferably in the form of a boss projecting from the lower portion of the crank case at one side thereof, and is normally closed by a plug 64. Through it the level of the oil in the crank case may be observed. Located within the crank case and secured to the bottom thereof is a pan 65, as shown in Figs. 3 and 5, which has a hole or perforation 66 in it a short distance above the bottom thereof for admitting oil from the crank case to said pan, and at that side of said pan adjacent to the engine cylinder 35 it is provided with an upwardly-projecting curved deflector 67, the purpose of which will be hereinafter explained. Arranged over and dipping into the pan 65 is a centrifugal governor 68 mounted on a transverse shaft 69 journaled in the side walls 19^a of the crank case, as best shown in Figs. 5 and 10. As shown in said figures, the governor 68 comprises 130

weighted levers 70 pivoted at 71 to diverging arms 72 which project from the inner end of the shaft 69, the levers 70 being provided with inwardly-projecting arms 73 which project toward the axis of the shaft 69. Therefore, as the governor rotates the weighted portions of the levers 70 tend to swing out or away from the shaft 69 while the outer ends of the arms 73 tend to move inwardly in substantial alignment with the axis of said shaft. This inward movement of the arms 73 is resisted by a spring 74 mounted on a rod 75 which extends axially through the shaft 69, and is provided with a head 76 at its inner end which underlies the inner ends of the arms 73, as best shown in Fig. 10. The spring 74 is fitted in a recess in the inner end portion of the shaft 69, and the inner end of said spring bears against an abutment formed at the inner end of said recess. By this construction the spring 74 tends to hold the governor in its normal position but yields to permit the governor levers to swing out under centrifugal action. The governor is so arranged with reference to the pan 65 that when it is rotated by the operation of the engine its arms 70 dip into the oil in said pan and consequently act to distribute it throughout the crank case, thereby lubricating the parts therein. The oil in the pan 65 is supplied thereto from the crank case by the hole 66, which arrangement provides a simple and accurate means for controlling the amount of oil thrown by the governor which is limited to the amount that will pass through the hole 66. The pan serves to keep out sediment which may accumulate in the bottom of the crank case, and the sides of the pan also serve as deflectors to direct the oil throughout the interior of the crank case. The deflector 67 is provided to prevent an excessive amount of oil from being thrown against the piston and into the cylinder, and in addition to this deflector I prefer also to provide a shield 76^a in the form of a plate which extends transversely of the crank case adjacent to the inner end of the cylinder 35 and between it and the pan 65, as shown in Fig. 3. Said shield is secured at its upper margin to a flange 77 projecting downwardly from the cover plate 37, and it is provided with a vertical slot wide enough for the passage of the pitman 51.

The outer end portions of the engine cylinder 35 and the water hopper 34 are shown in Figs. 6 and 8, from an inspection of which it will be seen that said cylinder is provided with a head 78 secured thereto by bolts 79, in which head are mounted an inlet valve 80 and an exhaust valve 81. These valves are provided, respectively, with valve stems 82, 83 fitted in suitable bearings in the cylinder head and provided with springs 84, 85 which serve to seat the valves 80, 81 by moving the valve stems 82, 83 longitudinally of the cylinder in an outward direction. Within the head 78 is an ignition chamber 86 and an exhaust chamber 87, as best shown in Fig. 8. The exhaust chamber 87 discharges through a muffler 88 in the form of a pipe flared at its outer end portion and provided with a screen 89 which extends across its larger diameter. The muffler 88 is a casting and the screen 89 is cast integral with it. The purpose of said screen is to muffle the sound, as well as to keep gas and flame from shooting out of the muffler, and if desired a plurality of said screens may be employed. The cylinder 35 is supplied with hydro-carbon liquid fuel from the fuel tank 18 through the pipe 30, said pipe connecting with an intake nozzle 90 which is integral with the cylinder head 78, as best shown in Figs. 1 and 6. As therein shown, said nozzle 90 extends downward from the port of the intake valve 80 and has an opening 91 at its lower end which may be wholly or partially closed by means of a swinging lid 92 pivoted to the nozzle at 93, as shown in Fig. 1. This opening is for the admission of air to the nozzle 90, which serves also as a mixing chamber for preparing the proper mixture of fuel and air before its admission to the cylinder. The fuel pipe 30 connects with the nozzle 90 at one side thereof adjacent to the opening 91, and it is provided with a valve seat at its discharge end adapted to cooperate with a needle valve 94 by which the quantity of fuel admitted to the nozzle may be regulated. It will be apparent from the foregoing description that the fuel is discharged into the nozzle 90 at right angles to the direction of its movement through said nozzle to the cylinder, which is an advantageous feature as by this means sufficient restriction is provided to make the engine operate effectively by suction to raise fuel from the tank which is at a lower level than the cylinder. By adjusting the air control plate 92 and needle valve 94 the mixture may be nicely regulated so as to secure the most efficient operation of the engine.

The intake valve 80 is opened by the suction of the piston, but mechanism must be provided for opening the exhaust valve 81 to purge the cylinder of consumed gases before the admission of a fresh charge of fuel. This is accomplished by means of a rocking lever 95 mounted intermediately on a pivot 96 in such position that one arm 95^a thereof extends over the exhaust valve stem 83. This arm carries a tappet 97 in the form of a bolt adjustably secured in said arm so that its normal distance from the outer end of the valve stem 83 may be adjusted. Obviously by rocking the lever 95 in the appropriate direction the tappet 97 will strike the valve stem 83 and move it inwardly thereby opening the exhaust valve. When the pressure

of the tappet is removed the spring 85 serves to restore the exhaust valve to its normal position in the usual way. A spring 98 connected with the lever 95 and with a standard 99 which carries the pivot 96 serves to hold the lever 95 in the position shown in Fig. 8, which is its normal inoperative position. The opposite arm 95^b of the lever 95 is connected with one end of a horizontally disposed operating rod 100 by the reciprocation of which said lever is rocked to alternately open and close the exhaust valve as the engine operates, the opposite end of said rod being supported by a suitable bearing 15 on the engine frame, in which it is arranged to slide. This reciprocation of the rod 100 is effected by means of a cam 101 carried by the shaft 61, as shown in Figs. 4 and 10. The edge of the cam 101 is in line with the 20 axis of the rod 100, and between the operating face of the cam and said rod is a follower lever 102 pivoted at its lower end on a pivot 103, and having no connection with said rod, which is supported independently 25 thereof, as shown in Figs. 1, 4 and 5. By this construction the direct thrust of the cam is transmitted to the rod 100 through said follower lever so that there is no side thrust on said rod. The follower lever 102 is provided with a laterally-projecting lug 104 adjacent to the end of the rod 100 for a purpose which will be hereinafter set forth.

Referring now to Fig. 1, 105 indicates a 30 bracket which is adjustably mounted on the rod 100, preferably by being clamped thereto by a bolt 106. Said bracket carries a trip bar 107, which at one end is connected with said bracket by a pivot 108 and adjacent to its pivot is provided with a spring 109 which tends to move the free end of the said bar upwardly, or in other words to rotate it in a clockwise direction as viewed in Fig. 1. The trip bar 107 actuates the 40 ignition devices which are of the make and break type, and the way in which this is done will now be described. Referring to Fig. 8, 110 indicates a stationary electrode which extends through a passage 111 in a 45 bracket 112 into the ignition chamber 86, said stationary electrode being held from electrical contact with said bracket and the passage closed by gaskets 113 of any suitable non-conducting material fitting into the 50 opposite ends thereof. At its inner end the electrode carries a contact point 114. In close proximity to the electrode 110 is a rotatable electrode 115 which also extends through a passage in the bracket 112 into the ignition chamber 86 where it is provided with a laterally-projecting arm 116 which carries a contact point 115^a adapted to engage or disengage the contact point 114 by rotation of the electrode 115. As shown in 55 Fig. 8, the bracket 112 provides a compara-

tively narrow inner bearing for the inner end portion of the electrode 115, and outside of said bearing the passage is widened, as shown at 117, so that considerable air space is provided around the electrode. The 70 purpose of this arrangement is to prevent the accumulation of carbon in the short inner bearing by maintaining that portion of the electrode and the bearing at a high temperature incident to the operation of the engine, leaving it to collect in the larger outside space where it will do no harm. The outer end of the electrode 115 projects through and is carried in an outer bearing in an arm 112^a, which forms a part of bracket 75 80 112. This outer bearing is axially aligned with said inner bearing in bracket 112.

Fixedly secured to the electrode 115 near the inner bearing is a clutch member 118 arranged to be percussively actuated by a 85 clutch member 119 which projects laterally from a hammer block 120 rotatably mounted upon the electrode 115 between its outer bearing 112^a and the clutch member 118. On the outer end of the electrode 115, which projects beyond the outer bearing arm 112^a, is a spring 122 one end of which is connected with said arm, and the other with the electrode 115, which spring may be arranged to rotate said electrode in either a clockwise or in a counter-clockwise direction as viewed in Figs. 1 and 13, so that it may operate either to normally hold the contact point 90 95 115^a in engagement with the contact point 114 for magneto ignition, as shown in Fig. 13, or, by reversing its outer end, it may also be made to hold contact point 115^a away from contact 110 for use with battery ignition. This spring also exerts end pressure on said electrode and tends to prevent 100 any end play thereof. One of the clutch members, in the present instance the member 119, is provided at its end adjacent to the opposite clutch member, 118, with a laterally-projecting lug 119^a, and the clutch member 118 is provided with a notch 118^a adapted to receive said lug so as to effect clutching engagement between said clutch members. The notch 118^a is, however, long 105 110 115 enough to permit considerable lost motion between said members, as illustrated in Fig. 13. The normal position of these parts is shown in the latter figure, from an inspection of which it will be seen that when the contact 115^a is in engagement with the contact 114 the clutch member 119 may rock to a considerable extent in a clockwise direction as viewed in said figure, independently of the clutch member 118, the object of which 120 is to permit the hammer block 120, which is integral with the clutch member 119, to swing through a limited arc in one direction without rotating the electrode 115. A spring 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 clutch member and the other with the clutch member 118, tends to hold the members of the clutch in the position shown in Fig. 13.

As shown in Fig. 1, the hammer block 120 extends diagonally downward from the electrode 115 and is provided at its lower margin with two flat or plane surfaces 124—125 disposed at an angle to each other and having a V-shaped notch 126 between them, which notch is adapted to be engaged by the free end of the trip bar 107. Adjacent to the notch 126 the hammer block 120 is provided with a plane surface 127 against which the upper surface of the trip bar 107 rests when it is in position to engage the notch 126. Bearing in mind the foregoing description of these parts, it will be manifest that when the parts are in the position shown in Fig. 1, at which time the contact points will be in the position shown in Fig. 13, and the exhaust valve will be in its closed position, if the rod 100 be moved to the left as viewed in Fig. 1, the trip bar 107, by reason of its engagement with the notch 126, will act to swing the hammer block 120 about the electrode 115 in a clockwise direction, thereby increasing the tension of the spring 128. In this operation the lug 119^a moves to the opposite end of the notch 118^a in clutch member 118, which remains stationary with contact 115^a in engagement with contact 114. As this movement of the hammer block continues the plane surface 125 of said hammer block will swing into engagement with the upper surface of the trip bar 107, moving the free end of said bar downward against the action of the spring 109 so that its free end will clear the point of the notch 126, thereby permitting the rod 100 and trip bar 107 to continue to move in the same direction without further rotation of the hammer block 120. As soon, however, as the trip bar 107 is clear of the notch 126 the spring 128 will act to rotate the hammer block with its clutch member 119 quickly and forcibly in the opposite direction. This reverse rotation of the hammer block will cause the lug 119^a of its clutch member 119 to travel back in the notch 118^a and act percussively in a circular direction upon the clutch member 118, against the tension of the spring 122, which it overcomes by its inertia, thereby rotating the electrode 115 in a counter-clockwise direction as seen in Fig. 13 so as to carry its contact point 115^a away from the contact point 114 of the fixed electrode 110, thus making a spark in the ignition or combustion chamber 86. Immediately after this takes place the electrode 115 will be reversely rotated and restored to its initial or normal position by the spring 122, which, as has been explained, tends to hold the contact 115^a in engagement with contact 114. By this construction the contact points are effectively

and very abruptly separated by the hammer-like blow delivered by the hammer block 120 through the clutch member 119 to the clutch member 118, which functions as a sort of anvil to take such blow and transmit it through the rotary electrode to the movable contact point carried thereby.

While the firing operation just described is occurring the operating rod 100 continues to move to the left as viewed in Fig. 1, and as its movement actuates the exhaust valve operating lever 95 so that it is rocked in a clockwise direction as viewed in Fig. 2, it will at the proper time actuate the exhaust valve to move it off its seat, thereby permitting the burnt gases in the cylinder to be discharged therefrom. These operations are, of course, properly timed so that the exhaust valve does not open until after the ignited charge has done its work. Continued rotation of the cam 101 obviously permits the parts to assume their normal position, the bar 100 being moved to the right as viewed in Fig. 1 under the action of the spring 98.

In engines of this type it is desirable to shut off the spark and hold the exhaust valve open while the fly-wheel continues to rotate above a critical speed, in order to economize fuel. In other words, sometimes the fly-wheel can make quite a number of revolutions between explosions without dropping below its critical speed, and in such circumstances it is desirable to shut off the spark and hold the exhaust valve open so that fuel will not be consumed except as needed, and in my improved engine this is accomplished by the action of the governor 70 operating through a detent lever 129 the construction of which is best shown in Fig. 7. This detent lever is in the form of a yoke having an intermediate portion 129^a and angularly-disposed arms 129^b, 129^c at its opposite ends. This yoke is mounted in a vertical position on a shaft 130, the ends of which are secured in the top plate 131 and bottom plate 132 of the chamber 55, as best shown in Figs. 5 and 10. The detent lever is, therefore, adapted to rock about a vertical axis, or an axis disposed transversely relatively to the axis of the follower 102. Near its upper end it is provided with a laterally-projecting dog 133 which is adapted to swing in behind the lug 104 carried by the follower lever 102. The relation of these parts when the dog 133 is not in its operative position is best shown in Figs. 4 and 5, and from the illustration of those figures it will be apparent that by rocking the detent lever 129 in the appropriate direction it may be carried back of the lug 104 so that it will operate to hold the operating rod 100 in its extreme position to the left as viewed in Fig. 1. When the rod 100 is in this position it will not be affected by the rotation of the

cam 101, and consequently the exhaust valve will be held open and the ignition apparatus will not be operated. The detent lever 129 is operated to accomplish this result by means of the governor 70 through the pin 75, the outer end of which is adapted to coact with an arm 133^a carried by said detent lever near the lower end thereof, as shown in Figs. 7 and 10, the arrangement being such that when the weighted levers of the governor swing outward, and consequently move the pin 75 to the left as viewed in Fig. 10, this movement of said pin will thrust outward on the arm 133^a, thereby rocking the detent lever 129 to move its dog 133 into operative engagement with the lug 104 of the follower lever 102, as above described. When the speed of the engine drops the pressure of the governor levers on the pin 75 is lessened so that said pin moves in the opposite direction under the action of the spring 74, whereupon the detent lever 129 is restored to its initial position by the action of a spring 134, one end of which is connected with an arm 135 carried by the detent lever 129 and the other end of which is connected to an adjusting screw 136 mounted in one of the walls of the chamber 55 and provided with an adjusting nut 137 by which the tension of the spring 134 may be regulated. As shown in Fig. 7, the detent lever 129 is made in one piece and is preferably of sheet steel pressed to shape and having its arm 133 tempered so that it will be capable of withstanding severe usage. By supporting said lever at its ends on the shaft 130, widely separated bearings are provided for it so that it is supported against twisting strains, and cannot easily get out of its proper position. By mounting said detent lever and its associated parts in the chamber 55, which, as best shown in Figs. 5 and 10, communicates with the crank case through suitable openings, the operating parts in said chamber are lubricated by the oil distributed in the crank case.

By the construction described the governor operates not only to keep the engine from attaining too high speed, but also regulates the ignition apparatus and the fuel supply so that the engine may be maintained in operation at a comparatively uniform speed without waste of fuel. Electric current is supplied to the fixed electrode 110 by a cable 138, one end of which is connected with the magneto and the other end with a connector 139 secured to said electrode. The other terminal of the magneto is grounded in any convenient way to the frame of the engine. By mounting the magneto outside of the crank case, as described, it is readily accessible and may be easily removed or replaced. The advantage of mounting the crank case on a separable base, as shown and described, is that the base can easily be

removed and changed for one of a different size, as might be necessary if it were desired to use a fly wheel of larger diameter than usual. By my improved construction, a crank case of standard size can be used with bases of different heights.

What I claim as my invention and desire to secure by Letters Patent, is—

1. In an internal combustion engine, the combination with a cylinder and piston, and an exhaust valve, of a reciprocating rod for actuating said valve, a rotating cam driven by said piston for moving said rod in one direction, a follower pivotally supported at one end on a fixed pivot and having its other end extending between said rod and said cam, a speed regulating governor driven by said piston, and means controlled thereby and acting on said follower for holding said valve open during the interval that the engine speed exceeds a predetermined maximum.

2. In an internal combustion engine, the combination with an engine frame, a cylinder and piston, and an exhaust valve, of a rocking lever for opening said valve, a horizontally disposed reciprocating rod for actuating said lever, a rotating cam driven by said piston for moving said rod in one direction, and a follower pivotally supported at one end on a fixed pivot and having its other end extending between said rod and said cam, with said rod and said cam having operative bearing against opposite sides of said follower, said rod being supported entirely independently of said follower.

3. In an internal combustion engine, the combination with a cylinder and piston, and an exhaust valve, of a rocking lever for opening said valve, a reciprocating rod for actuating said lever, a rotating cam driven by said piston for moving said rod in one direction, a pivotally mounted follower interposed between said cam and the adjacent end of said rod, a laterally projecting lug carried by said follower, and a governor controlled rocking detent lever having its axis disposed transversely relatively to the axis of the follower, and adapted to cooperate with said lug to hold the reciprocating rod in position with the exhaust valve open.

4. In an internal combustion engine, the combination with a cylinder and piston, ignition devices for causing a spark in said cylinder, and an exhaust valve, of a rocking lever for opening said valve, a horizontally disposed reciprocating rod for actuating said lever and said ignition devices, a rotating cam driven by said piston for moving said rod in one direction, and a vertically disposed flat follower pivotally mounted at one end and interposed between said cam and the adjacent end of said rod.

5. In an internal combustion engine, the combination with an engine frame, a cylin-

der and piston, ignition devices for causing a spark in said cylinder, and an exhaust valve, of a rocking lever for opening said valve, a reciprocating rod for actuating said lever and said ignition devices, a rotating cam driven by said piston for moving said rod in one direction, and a vertically disposed follower pivotally mounted at one end and interposed between said cam and the adjacent end of said rod, said rod being supported entirely independently of said follower.

6. In an internal combustion engine, the combination with a cylinder and piston, ignition devices for causing a spark in said cylinder, and an exhaust valve, of a rocking lever for opening said valve, a reciprocating rod for actuating said lever and said ignition devices, a rotating cam driven by said piston for moving said rod in one direction, a pivotally mounted follower interposed between said cam and the adjacent end of said rod, a laterally projecting lug carried by said follower, and a governor controlled rocking 25 detent lever having its axis disposed transversely relatively to the axis of said follower, and adapted to cooperate with said lug to hold the reciprocating rod in position with the exhaust valve open.

30 7. In an internal combustion engine, the combination with an engine frame comprising a crank case, a cylinder, a piston operating therein, ignition devices for causing a spark in said cylinder, and an exhaust valve associated with said cylinder, of a chamber at one side of said frame, and outside of said crank case, a reciprocating rod actuated by the operation of the piston for opening said exhaust valve at intervals and for actuating 35 said ignition apparatus, one end of said rod extending into said chamber, a rocking detent mounted in said chamber and movable into position to hold said rod in its valve-opening position, and a governor in said 40 crank case for controlling the operation of said detent.

8. In an internal combustion engine, the combination with an engine frame, a cylinder, a piston operating therein, ignition devices for causing a spark in said cylinder, and an exhaust valve associated with said cylinder, of a chamber at one side of said frame, a reciprocating rod actuated by the operation of the piston for opening said exhaust valve at intervals and for actuating 50 said ignition apparatus, one end of said rod extending into said chamber, a rocking detent mounted in said chamber and movable into position to hold said rod in its valve-opening position, a governor for moving said detent to its operative position, and a spring for returning said detent to its normal position.

9. In an internal combustion engine, the combination with a crank case, a crank shaft

supported thereby, and a chamber outside of said crank case and communicating therewith, of a cylinder, a piston connected with said crank shaft, an exhaust valve associated with said cylinder, an actuating rod for opening said exhaust valve, said rod extending into said chamber, means in said chamber for actuating said rod, and a governor in said crank case for controlling the operation of said actuating means.

10. In an internal combustion engine, the combination with a crank case, a crank shaft supported thereby, and a chamber outside of said crank case and communicating therewith, of a cylinder, a piston connected with said crank shaft, an exhaust valve associated with said cylinder, an actuating rod for opening said exhaust valve, said rod extending into said chamber, means in said chamber for actuating said rod, a detent lever mounted in said chamber and adapted to operate to hold said rod in position to hold the valve open, and means in said crank case for controlling the operation of said detent lever.

11. In an internal combustion engine, the combination with a crank case, a crank shaft supported thereby, and a chamber at one side of said crank case and communicating therewith, of a cylinder, a piston connected with said crank shaft, an exhaust valve associated with said cylinder, an actuating rod for opening said exhaust valve, said rod extending into said chamber, means in said chamber for actuating said rod, a detent lever mounted in said chamber and adapted to operate to hold said rod in position to hold the valve open, and means in said crank case for supplying oil therefrom to said chamber.

12. In an internal combustion engine, the combination with a crank case, a crank shaft supported thereby, and a chamber at one side of said crank case and communicating therewith, of a cylinder, a piston connected with said crank shaft, an exhaust valve associated with said cylinder, an actuating rod for opening said exhaust valve, said rod extending into said chamber, means in said chamber for actuating said rod, a detent lever mounted in said chamber and adapted to operate to hold said rod in position to hold the valve open, and a governor operating in said crank case to distribute oil therein and adapted to control the operation of said detent lever.

13. In an internal combustion engine, the combination with a crank case, a crank shaft supported thereby, of a chamber outside of said crank case and communicating therewith, a cylinder, a piston connected with said crank shaft, an exhaust valve associated with said cylinder, an actuating rod for opening said exhaust valve, said rod extending into said chamber, means in said chamber for actuating said rod, and a governor in said crank case for controlling the operation

of said actuating means, said governor also effecting a distribution of oil within said crank case and into said chamber.

14. In an internal combustion engine, the combination with a crank case, a crank shaft supported thereby, a cylinder, and a piston connected with said crank shaft and operating in said cylinder, of an exhaust valve associated with said cylinder, an actuating rod for opening said exhaust valve, means outside of the crank case and driven from the crank shaft, for actuating said rod, and means in said crank case for controlling the operation of the actuating means for said rod, said latter means also effecting a distribution of lubricant within said crank case.

15. In an internal combustion engine, the combination with a crank case, a crank shaft supported thereby, a cylinder, and a piston connected with said crank shaft and operating in said cylinder, of an exhaust valve associated with said cylinder, an actuating rod for opening said exhaust valve, means outside of the crank case and driven from the crank shaft, for actuating said rod, a detent lever mounted outside of the crank case and adapted to operate to hold said rod in position to hold said valve open, and means in said crank case for controlling the operation of said detent lever, said latter means also effecting a distribution of lubricant within said crank case.

16. In an internal combustion engine, the combination with a crank case, a crank shaft supported thereby, and a chamber at one side of said crank case and communicating therewith, of a cylinder, ignition devices for causing a spark in said cylinder, a piston connected with said crank shaft, an exhaust valve associated with said cylinder, an actuating rod for opening said exhaust valve and actuating said ignition devices, said rod extending into said chamber, means in said chamber for actuating said rod, a detent lever mounted in said chamber and adapted to

operate to hold said rod in position to hold the valve open, and means in said crank case for supplying oil therefrom to said chamber.

17. In an internal combustion engine, the combination with a crank case, a crank shaft supported thereby, and a chamber at one side of said crank case and communicating therewith, of a cylinder, ignition devices for causing a spark in said cylinder, a piston connected with said crank shaft, an exhaust valve associated with said cylinder, an actuating rod for opening said exhaust valve and actuating said ignition devices, said rod extending into said chamber, means in said chamber for actuating said rod, a detent lever mounted in said chamber and adapted to operate to hold said rod in position to hold the valve open, and a governor operating in said crank case to distribute oil therein and adapted to control the operation of said detent lever.

18. A detent lever for the purpose described, comprising a single piece of steel having its ends bent over to form arms for pivotally supporting said lever, a laterally-projecting dog at one side thereof, a laterally-projecting arm at the opposite side thereof by means of which said detent lever may be rocked in one direction, and a third arm adapted to be connected with a spring by means of which said detent lever may be rocked in the opposite direction.

19. A detent lever for the purpose described, comprising a single piece of steel having angularly disposed arms at its ends for pivotally supporting said lever, a laterally projecting dog at one side thereof adapted for engagement with a valve cam follower, and an arm projecting laterally from the opposite side thereof adapted to contact with a governor operated push rod, the rod contacting face of said latter arm being disposed radially with respect to the pivotal axis of said detent lever.

HAROLD E. McCRAY.
